22 Claims. (Cl. 101—65)

1

This invention relates to addressing and like printing machines. Machines of this character are known in which the printing head or pad carrier is pivotally mounted on a reciprocating body and carries two printing pads shaped to effect printing from different parts of the embossed printing plates. The movement of the reciprocating body causes oscillation of the pad carrier between successive printing strokes so that each pad is brought into operative position alternately and two different prints are made from each of the plates. Machines are also known in which the head or pad carrier is rotatably mounted on a reciprocating body and carries three differently shaped pads, the pad carrier being partially rotated between successive printing strokes so that the pads are brought successively into operative position in cyclic order and three different prints are made from each of the plates.

The present invention consists broadly of an addressing or like printing machine, comprising a rotatable pad carrier which carries at least three printing pads at intervals round its axis of rotation, a body on which said pad carrier is rotatably mounted, and which reciprocates and thereby moves said pad carrier bodily to and from a printing position, manually operable control means, and means whereby, according to the setting of said control means, said pad carrier can be either oscillated to and fro about its axis of rotation as said body reciprocates, so that two of the printing pads are alternately operative when said pad carrier is moved successively to the printing position, or rotated unidirectionally step by step as said body reciprocates, so that all of said printing pads are successively operative in cyclic order when said pad carrier is moved successively to the printing position.

In order that the invention may be the more clearly understood a machine in accordance therewith will now be described, reference being made to the accompanying drawings wherein:

Figure 1 is a perspective view of the machine with the printing head in the lowered or printing position.

Figure 2 is a side elevation of the same looking from the left of Figure 1.

Figure 3 is a section on line III—III of Figure 2.

Figure 4 is a section on line IV—IV of Figure 3.

Figure 5 is a section on line V—V of Figure 3.

Figure 6 is a plan of a part of the machine.

Figure 7 is a section on line VIII—VIII of Figure 6 but with the control lever at a different setting from that of Figure 6.

2

Figure 8 is a similar view to Figure 7 but with the control lever at the setting of Figure 6.

Figure 9 is a similar view to Figures 7 and 8 but with the control lever at a third setting.

Figure 10 is a section on line X—X of Figure 6 but with the printing head at the raised position.

Referring to the drawings, the machine comprises a main oscillatable body 1 which oscillates about a horizontal axis 2 by virtue of two lugs 3 and 4 formed integral with said body, which lugs have aligned holes 5 and 6 through which a fixed horizontal shaft 7 (Figure 2) passes. The lug 4 extends beyond said shaft 7, and mechanism attached to the extending portion of said lug serves to oscillate the body 1 about said shaft and thus about said axis 2.

Said body 1 is also formed with two integral arms 8 and 9 the ends of which carry bearings for a rotatable horizontal shaft 10 which is parallel to, and spaced some distance from, the shaft 7. This shaft 10 has mounted fast upon it a hub element 11 which is formed with three radial spokes 12 equally spaced at 120 degrees from each other. Three pad holders 13, for pads not shown, are mounted on the ends of the respective spokes 12. When the body 1 is rotated upwardly about the axis 2, the pad holders 13 are lifted to the nonprinting position. When said body is rotated downwardly about the axis 2, the pad holder 13 which, for the time being is undermost, is lowered to the printing position.

Mechanism is provided whereby, in response to the up and down movement of the body 1 about the axis 2, the shaft 10 is given steps of rotation. This mechanism is subject to control by a control lever 14 mounted fast on the upper end of a shaft 15 which rotates in bearings 16 and 17 carried by the body 1. This lever 14 has three positions and the arrangement is such that, when said lever is at position "one," the raising and lowering of the body 1 is without effect on the shaft 10 so that the same pad holder 13 is lowered to the printing position each successive time the body 1 is lowered. When said lever 14 is at position "two" each upward movement of the body 1 effects the rotation of the shaft 10 through 120 degrees, the direction of each rotation being reversed each time so that two only of the pad holders 13 are alternately lowered to the printing position as the body is successively lowered. When said lever 14 is at position "three," each upward movement of the body 1 effects rotation of the shaft 10 through 120 degrees, but, in this case the direction of rotation is always the same so that the three pad holders 13

are successively brought to the printing position in cyclic order as the body 1 is successively lowered.

Describing now the mechanism by which the shaft 10 is rotated as set forth, the body 1 is formed with two further lugs 18 and 19 whose ends carry bearings for a horizontal shaft 20 which is parallel to the shafts 7 and 10. A fixed toothed sector 21 (Figure 2) is provided which is fixed to the stationary base of the machine, and a gear train is provided which couples said sector to a pinion 22 which is loosely rotatable on the shaft 20, said gear train consisting of a gear wheel 23 carried by the lug 18 and in mesh with said sector, and a double gear wheel carried by said lug 18 and having its smaller gear 24 in mesh with the gear wheel 23 and its larger gear 25 in mesh with the pinion 22. Thus, as the body 1 is oscillated to and fro about the axis 2, the gear wheel 23 rolls along the teeth of the sector 21 and is thereby rotated in opposite directions, and this imparts a greater rotation in opposite directions to the double gear wheel 24, 25, and this in turn imparts a still greater rotation in opposite directions to the pinion 22. Actually the angle of oscillation of the body 1 is small, and the angle through which the pinion 22 oscillates is rather more than 180 degrees.

The pinion 22 is fast with a pawl plate 26 which carries two pawls 27 and 28 which are biased into engagement with the periphery of a ratchet wheel 29 which is fast on the shaft 20. Mounted on the shaft 20 so as to be longitudinally reciprocatable is a sleeve unit comprising a pawl-actuating flange 30. The edge of this flange is bevelled or coned on the side which faces the pawls 27 and 28 as clearly shown in Figure 6. The lever 14 has an extension 31 beyond the shaft 15, and this carries at its end a roller 32 which engages in a circumferential groove 33 on said sleeve unit, so that said sleeve unit is slid along the shaft 20 in response to the movements of the lever 14. The pawls 27 and 28 carry respective rods 34 and 35 rigid therewith and projecting parallel to the shaft 20. The arrangement is such that, when the lever 14 is at position "one" the flange 30 is at its extreme right hand position (according to Figure 6) and its bevelled edge engages, and presses outwardly away from the ratchet wheel 29, both the rods 34 and 35, as in Figure 7, and thus the rotation of the pinion 22 and pawl plate 26 has no effect on the ratchet wheel 29 and shaft 20, and the latter accordingly remains without rotating during the up and down movement of the body 1.

When the lever 14 is at position "two" the flange 30 occupies a mid position at which the rod 34 is still engaged by the edge of said flange and the pawl 27 is accordingly still out of engagement with the ratchet wheel 29, but at which the rod 35 (which is shorter than the rod 34) is clear of said flange 30, and the pawl 28 therefore engages the periphery of the ratchet wheel 29. The position is now as in Figure 8. The pawl 28 is adapted to engage two shoulders 36 on the periphery of the ratchet wheel 29 at 180 degrees from one another, and it will be seen that, as the pinion 22 and pawl plate 26 oscillate to and fro through just more than 180 degrees, the pawl 28 will, with each oscillation in one direction, rotate the ratchet wheel 29 and therefore the shaft 20 through 180 degrees. In other words the shaft 20 will be rotated uni-

directionally through steps of 180 degrees, and, in practice, each such step of rotation takes place during the up movement of the body 1 away from the printing position.

When the lever 14 is at position "three," the flange 30 occupies an extreme left hand position at which both the rods 34 and 35 are disengaged by the edge of said flange so that both pawls 27 and 28 engage the periphery of the ratchet wheel 29 as in Figure 9. The pawl 27 is adapted to engage a shoulder 37 of the ratchet wheel so as to rotate the ratchet wheel in the opposite direction to the pawl 28 when engaging a shoulder 36, and thus, when the lever 14 is at the said position "three," the ratchet wheel and therefore the shaft 20 will be rotated to and fro through 180 degrees, with the pawl plate 26 and pinion 22. In other words the shaft will be rotated through 180 degrees in one direction during the down stroke of the body, and through 180 degrees in the other direction during the up stroke of the body.

At its left hand end (according to Figure 6) the shaft 20 has a crank 38 mounted on it, and the end of said crank is pin jointed to one end of a rack bar 39 which is formed with rack teeth 40. The rack teeth 40 engage with a gear wheel 41 which rotates freely on the shaft 10. Said gear wheel 41 carries two pawls 42 and 43 which are biased, by means of leaf springs 44 and 45, into engagement with the periphery of a ratchet wheel 46 which is fast on said shaft 10. Said ratchet wheel 46 has three teeth 47 at 120 degrees to each other which are adapted to be engaged by the pawl 42 for rotation of the ratchet wheel in one direction, and one teeth 48 adapted to be engaged by the pawl 43 for rotation of said ratchet wheel in the other direction. The lower end of the shaft 15 has rigidly mounted on it an arm 49 whose extremity is formed with a slot in which engages a pin 50 which projects downwardly from a horizontal bar 51 which is mounted on the body 1 so as to be longitudinally reciprocatable. This bar carries at its end a finger 52 which is adapted to engage a tail extension 53 on the pawl 43 in a manner which will hereinafter appear.

The arrangement is such that, each time the shaft 20 makes a step of rotation through 180 degrees, the crank 38 moves from one extreme position to the other and the consequent longitudinal stroke of the rack bar 39 causes the gear wheel 41 to rotate through more than 120 degrees.

As has been heretofore described, when the lever 14 is at position "one" the shaft 20 does not make any rotary movement as the body 1 is raised and lowered, and therefore the rack bar 39 does not make any longitudinal movement, and the gear wheel 41 does not make any rotary movement, and neither do the ratchet wheel 46 and the shaft 10. Each time, therefore, the body 1 is lowered the same pad holder 13 is brought down to the printing position.

When the lever 14 is at position "two," the shaft 20, as before described, makes a series of unidirectional movements through 180 degrees, each movement taking place when the body 1 makes its up stroke. Therefore the rack bar 39 makes a series of strokes in alternate directions and the gear wheel 41 rotates to and fro through more than 120 degrees, each rotation taking place when the body 1 makes its up strokes. At this time both pawls 42 and 43 are in engagement with

the ratchet wheel 46, and, when the gear wheel 41 makes its rotary movement in one direction, the pawl 43 engages the tooth 48 and thereby rotates the ratchet wheel 46 and therefore the shaft 10 in the said one direction, the amount of such rotation being exactly 120 degrees. When said gear wheel 41 makes its rotary movement in the other direction, the pawl 42 engages the adjacent tooth 47 and thereby rotates the ratchet wheel 46 and the shaft 10 in said other direction, the amount of such rotation being again exactly 120 degrees. In other words when the lever 14 is at position "two," the shaft 20 is rotated to and fro through 120 degrees, each rotation taking place during the up stroke of the body 1. Thus successive descents of the body 1 bring two of the pad holders 13 down to the printing position alternately.

When the lever 14 is at position "three," the shaft 20, as before described rotates to and fro through 180 degrees, the rotation being in one direction when the body 1 makes its up stroke, and in the other direction when said body makes its down stroke. Therefore the rack bar 39 makes a series of strokes in alternate directions, a complete reciprocation to and fro being made for each up-and-down movement of the body 1. This means that the frequency of reciprocation of the rack bar is double what it is when the lever 14 is at position "two." The gear wheel 41 therefore rotates to and fro at a frequency double that when the lever 14 is at position "two."

When said gear wheel 41 rotates in one direction the pawl 42 engages a tooth 47 to rotate the ratchet wheel 46 through 120 degrees as before, and this is arranged to take place during the up stroke of the body 1. Owing, however, to the lever 14 being at position "three," the finger 52 is now in such a position that, when the gear wheel 41 rotates in the other direction the tail extension 53 of the pawl 43 engages the finger 52 the moment before said pawl 43 is due to engage the tooth 48 so that said pawl is forced against its spring bias and misses said tooth. Thus only the pawl 42 is operative and the ratchet wheel and therefore the shaft 10 continue to be rotated unidirectionally through 120 degrees, each step of rotation taking place when the body 1 makes its up stroke. Thus successive descents of the body 1 bring all three of the pad holders 13 down to the printing position successively in cyclic order.

In order to ensure that the shaft 10 is rigidly locked at each of its three angular positions during the descent to the printing position, said shaft has an indexing disc 54 mounted fast on it by means of a cotter pin 54a; which indexing disc is formed with three notches 55 in its periphery equally spaced at 120 degrees from each other. Said indexing disc is adjacent the lug 8, and a corresponding indexing lever 56 is pivotally mounted, at a point 57 between its ends, on said lug 8 and has a bent-over end 58 which is adapted to engage in the notches 55 to lock said indexing disc, and therefore the shaft 10, at said three angular positions. At its other end said lever 56 is pin jointed at 59 to one end of a link 60. The other end of said link 60 is bifurcated, and the two branches 61 straddle a boss 62 mounted on the shaft 20. Thus the link 60 is supported for longitudinal reciprocation, and, by such longitudinal reciprocation, it rocks the lever 56 to bring its end 58 into and out of engagement with the periphery of the indexing disc 54.

The reciprocation of said link 60 is effected by 75

means of a cam 63 mounted fast on the shaft 20, say integral with the boss 62. The link 60 carries a roller 64, and is longitudinally biased by means of a tension spring 65 having one end connected to a stud 66 mounted on said link, and the other end connected to a stud 67 mounted on the plug 19, so that said roller bears against the periphery of said cam 63. Thus the link 60 is reciprocated according to the contour of the cam 63.

10 The contour of said cam 63 is such that, just after the commencement of each of the angular movements of the shaft 20 through 180 degrees, the end 58 of the lever 56 is moved out of engagement with the indexing disc 54 leaving the shaft 10 free to rotate, and, at all other times, the said lever end 58 bears against the periphery of said disc 54 under the influence of the spring 65.

15 It will now be understood that, when the lever 14 is at position "one" and the shaft 20 does not rotate at all, the lever end 58 will remain permanently in engagement with a notch 55 so that the shaft 10 will remain permanently locked with one pad holder 13 always at the position for printing.

20 When the lever 14 is at position "two," the shaft 20, as before described, makes a series of unidirectional rotations of 180 degrees, each such rotation being made during the up stroke of the body 1. These 180 degree rotations of the shaft 20 effect rotation of the shaft 10 through 120 degrees in opposite directions alternately. At the commencement of each of said 180 degree rotations of the shaft 20 the lever-end 58 is in engagement with a notch 55 and the shaft 10 is therefore locked.

25 It will be seen from Figure 5 that the connection between the gear wheel 41 and the ratchet wheel 46 by the pawls 42 and 43 is a lost motion connection such that the gear wheel 41 rotates a little distance in each direction before the rotation of the ratchet wheel 46 commences. This, added to the fact that the crank 38 is at the dead centre position at the commencement of each 180 degree rotation of the shaft 20, ensures that the shaft 20 always rotates some considerable distance before the rotation of the shaft 10 commences. During this initial lost motion of the shaft 20 the lever-end 58 is moved clear of the indexing disc and it is maintained clear of said indexing disc until the notch 45 has moved away from said lever end, whereupon said lever-end is released to bear against the periphery of said indexing disc, so that it springs into the next notch 45 at the end of the 120 degree movement of said shaft 10, and thus locks the shaft 10 at its new position.

30 When the lever 14 is at position "three," the shaft 20, as before described, rotates to and fro through 180 degrees, the rotation in the one direction being during the up stroke of the body, and that in the other direction being during the down stroke of the body. Each of the 180 degree rotations during the down stroke of the body is without effect on the shaft 10, but each of the 180 degree rotations during the up stroke of the body effects a 120 degree rotation of the shaft 10, always in the same direction. At the commencement of each 180 degree rotation of the shaft 20 during the down stroke of the body, the lever end 58 will be lifted from its notch 55, but, as the shaft 10 does not rotate at this time, said lever end will simply return to the same notch and the shaft will be again locked long before the printing position is reached.

35 The operation of the locking mechanism dur-

ing each 180 degree rotation of the shaft 20 during the up stroke of the body is the same as at position "two" of the lever, the lever end 58 being first withdrawn from its notch 55 in the indexing disc 54 to allow the shaft 10 to commence its 120 degree rotation, and thereafter bearing against the periphery of said indexing disc until it springs into the next notch 55 at the end of said 120 degree rotation.

It is necessary to provide means for preventing movement of the lever 14 from any one of its three positions to another except when the body 1 is at rest at its up position. To this end, the aforesaid sleeve unit which comprises the pawl-actuating flange 30, is caused to rotate to and fro with the pawl plate 26, and a gate element 68 is provided, mounted rigidly on the body 1, which prevents axial movement of said sleeve unit except when its rotary position is that corresponding to the up position of the body 1.

To cause said sleeve unit to rotate to and fro with the pawl plate 26 a peg 69 projects rigidly from said pawl plate parallel to the shaft 20 and engages in a notch 70 in the edge of said flange 30. The gate element 68 consists of an outer ring carrying within it an inner ring 71 surrounding the shaft 20 coaxially. The aforesaid sleeve unit comprises a boss 72 which carries a radially projecting stud 73. The inner ring 71 has its inner periphery formed with a circumferential groove 74 and the two inwardly projecting flanges constituted on each side of said groove 74 have notches 75 formed therein both at the same angular position as that which the stud 73 occupies when the body 1 is at the up position.

It will be seen that, when the lever 14 is at position "two," the stud 73 is within the circumferential groove 74, and that the sleeve unit can move to positions "one" or "three" only by said stud 73 passing through one or other of the notches 75, and this can only be when the body 1 is at the up position.

Indexing means are also provided for retaining the lever 14 at each of its three positions. Thus said lever is formed at its outer end with a boss 76 through which passes axially a rod 77. The upper end of this rod carries a hand knob 78 and said rod is biased downwardly by means of a spring (not seen) within the boss 76 to a position at which its lower end projects beyond the lower end of said boss into one or other of three holes formed in a fixed block 79 mounted on the body 1. Thus to change from one position to another the knob 78 is lifted to withdraw the end of the rod 77 from one hole in the block 79, and the lever is then moved to the new position and the end of the rod 77 is permitted to spring into the new hole.

Describing now certain of the constructional features of the machine, the hub element 11 is mounted on the shaft 10 by means of a cotter pin 80 (Figure 3). For mounting the pad holders 13 on the ends of the spokes 12 of said hub element, each of said spokes 12 is formed with a bore hole 81 which passes axially through it (i. e. radially with respect to the shaft 10) right to said shaft 10. Slidable in this bore hole 81 is a cylindrical rod 82, and, extending rigidly from the inner end of said cylindrical rod is a rod 83 of smaller diameter which passes through a diametrical hole 84 in the shaft 10. Rigidly mounted transversely on the outer end of said rod 82 is a plate 85, and said plate 85, and therefore the rods 82 and 83 are inwardly biased by means of tension springs 86 which are connected at their outer

ends to said plate 85 and at their inner ends to the hub element 11 by means of pins 87 mounted transversely across holes 88 bored into the spoke 12 on each side of the bore hole 81.

The hub element 11 is formed with a tapped radial hole 89 which is coaxial with, and diametrically opposite to, the bore hole 81, and screwed into this tapped hole is a screwed rod 90. The rod 83 passes completely through the shaft 10 and its end abuts against the end of said screwed rod 90 under the influence of the springs 86, and it will be seen that, in this way the rod 82 and plate 85 are firmly mounted on the spoke 12, and that, by adjusting the screwed rod 90, the distance of said plate 85 from the shaft 10 will be accurately adjusted. The adjustment of said screwed rod 90 is effected by means of a milled knob 91 mounted fast on the end thereof, and a milled lock nut 92 is provided for locking said rod 90 at any adjusted position.

The pad holder 13 is mounted on the outer face of the plate 85. Thus the two adjacent faces of said plate and pad holder are formed with cupped recesses, and these engage with opposite sides of an intermediate ball 93. Said pad holder and plate are drawn towards each other by means of four screwed bolts 94, so that said ball is under compression between said pad holder and plate, and it will be seen that by adjusting said bolts 94 the pad holder can be adjusted to any desired angular position about the centre of the ball. Then said pad holder can be adjusted so that the pad will abut flush against the printing plate.

It will be seen that, as there are three diametrical holes 84 in the shaft 10 for receiving the three rods 83, the said diametrical holes must be at different positions longitudinally of said shaft, as indicated in Figure 3. This of course means that the spokes 12 and the plates 85 will also be at slightly different positions longitudinally of the shaft. The pad holders 13 are, however, all at the same position longitudinally of the shaft, and thus the pad holders have their centres out of alignment with the centres of the plates 85 in two of the three cases.

It will be seen that, for biasing the pawls 27 and 28 into engagement with the ratchet wheel 29, said pawls have pins 95 and 96 mounted thereon on the side which is towards the pawl plate 26. These pins pass, through notches 97 and 98 in said pawl plate, to the opposite side of said pawl plate when each pin is connected to one end of a tension spring 99 whose other end is secured to a boss 100 which is integral with said pawl plate.

The mounting of the crank 38 on the shaft 20 is such that the connection between said shaft and said crank when the rotation is in the direction for driving the shaft 10 (i. e. when the body 1 is moving upwardly) is a yielding connection. This is to prevent shocks, for example on the pawls 42 and 43 when the drive takes up on said shaft 10. The connection between the shaft 20 and the crank 38 in the other direction is positive but no yielding or cushioning is required in that direction because there is no drive to the shaft 10.

Thus the crank proper 38 has a hole through it by which it is mounted loosely on said shaft 20. A connecting block 101 is mounted fast on said shaft 20. The crank 38 lies in a slot or groove 102 in said connecting block, the two sides or walls 103 and 104 of which slot or groove afford positive driving connection between said

block and said crank for opposite directions of rotation of said shaft. Said sides 103 and 104 are spaced so as to afford a lost motion connection between said block and said crank. A spring not shown biases said crank relative to said block so that it normally engages the side 103 of the groove 102. Thus it will be seen that, for counterclockwise rotation (according to Figure 2) of the shaft 20 the drive to the crank is a yielding or cushioning drive, whereas for clockwise rotation the drive is positive. The counterclockwise rotation is the direction for driving the shaft 10.

The groove 102 is open at the left hand side (according to Figure 6) of the connecting block 101 and the crank 38 is retained in place in said groove by means of a plate 105.

As is best seen in Figure 5, the ratchet wheel 46 is located in the hollow interior of the gear wheel 41, and said gear wheel 41 is formed with slots 106 and 107 in which are mounted the pawls 42 and 43. The rack bar 39 reciprocates in the usual type of housing 108 which is oscillatably mounted on the shaft 10 and maintains the rack teeth in engagement with the gear wheel 41. For mounting said gear wheel 41 on the shaft 10 said gear wheel is formed integral with a boss 126 which is secured to said shaft by means of a cotter pin 127.

It is desirable to apply a slight friction drag to the rotation both of the shaft 20 and the shaft 10. In the case of the shaft 20 such friction drag is applied by means of a friction pad or washer 109 which is in compression between a plate 110 which is fixed against rotation and a plate 111 which is fast on said shaft 20. The plate 110 is axially slidable on the shaft 20 and is biased against the pad 109 by means of a compression spring 112 which is in compression between said plate and the fixed lug 19. Said plate 110 is prevented from rotating by means of a pin 113 which is secured fast to said plate and projects parallel to the shaft 20 into a hole bored in the lug 19.

In the case of the shaft 10 the friction drag is applied by means of a friction washer or pad 114 which is in compression between a plate 115 which is fixed against rotation and a plate 116 which is fast with said shaft 10. Said plate 115 is axially slidable on said shaft 10 and is biased against the pad 114 by means of a number of compression springs 116 in compression between said plate and a pressure plate 117 which is mounted on the fixed lug 9. As will be clear from Figure 3, the springs 116 pass through holes 118 in the lug 9 to the far side of the latter where they abut against the pressure plate 117. Said pressure plate 117 is mounted by means of a screwed shank 119 which passes through the centre thereof and screws into a boss 120 mounted on a plate 121 which is secured by screws 122 fast on said lug 9. A milled head 123 on said screwed shank 119 restrains the pressure plate 117 against movement under the influence of the springs 116, and it will be seen that, by adjusting said screwed shank by means of said milled head, the compression of said springs, and therefore the amount of friction drag can be adjusted. The means for preventing the plate 115 from rotating consist of a number of pegs 124 mounted on said plate and extending parallel to the shaft 10 into holes 125 in the fixed lug 9.

It will be seen that the springs 116 bias the shaft 10 as a whole to the right according to Figure 3. This is resisted by means of a second

friction pad 126 between the cam 54 and the lug 8.

The reference 129 designates a guard. This is mounted on a rotatable shaft 130 supported by lugs 131 on the bottom of the body 1.

5 I claim:

1. In an addressing or like printing machine a body mounted for reciprocating movement to and from a printing position, a pad carrier rotatably supported on said body, at least three printing pads mounted on said body at intervals around its axis of rotation, adjustable driving means for effecting partial rotations of said pad carrier upon reciprocating movement of said body, said driving means being effective in one condition of adjustment to cause partial rotations of said pad carrier in opposite directions alternately and in another condition of adjustment to cause unidirectional partial rotations of said pad carrier, and manually operable control means for adjusting said driving means to either of said conditions.

2. A machine as claimed in claim 1, wherein said driving means comprise an oscillating element rotatably mounted on said body, means effective in said first condition of adjustment to oscillate said oscillating element at half the frequency of reciprocation of said body and in said second condition of adjustment to oscillate said oscillating element at the frequency of oscillation of said body, coupling means between said oscillating element and said pad carrier effective both in said first and said second condition of adjustment to cause partial rotation of said pad carrier upon movement of said oscillating element in one direction and additional coupling means between said oscillating member and said pad carrier effective only in said first condition of adjustment to cause reverse partial rotation of said pad carrier upon movement of said oscillating member in the reverse direction.

3. A machine as claimed in claim 2, wherein said means for effecting oscillation of said oscillating element comprise a shaft rotatably mounted on said body, means effective both in said first and in said second condition of adjustment to cause a half revolution of said shaft in one direction in response to movement of said body in one direction, means effective only in said second condition of adjustment to cause a half revolution of said shaft in the reverse direction in response to reverse movement of said body, and coupling means between said shaft and said oscillating element effective to move said oscillating element in opposite directions alternately in response to successive half revolutions of said shaft.

4. A machine as claimed in claim 3, wherein said means for effecting rotation of said shaft comprise a second oscillating element rotatably mounted on said body, means for rotating said second oscillating element in opposite directions in response to movements of said body to and from said printing position respectively, coupling means between said second oscillating element and said shaft effective in said first condition of adjustment to transmit rotary movement in one direction only and in said second condition of adjustment to transmit rotary movement in both directions.

5. A machine as claimed in claim 4 wherein said coupling means between said shaft and said first oscillating element comprises a crank fast to said shaft, a pinion fast to said oscillating

11

element, and a rack pivotally connected to said crank and meshing with said pinion.

6. A machine according to claim 5, wherein the said coupling means between said second oscillating element and said shaft comprises a pawl- and ratchet-wheel connection including two pawls for engaging a ratchet wheel for transmission in opposite directions respectively, and means are provided rendering one of said pawls inoperative when said manually operable control means are set for oscillation of said pad carrier and rendering both of said pawls operative when said control means are set for unidirectional step-by-step rotation of said pad carrier.

7. A machine according to claim 6, wherein one of said pawls has a peg projecting from it parallel to the axis of rotation of said ratchet wheel, and an actuating member is provided mounted axially slidably along said axis of rotation, said actuating member being positioned to engage said peg and thereby to hold said one pawl out of engagement with the ratchet wheel when said manually operable control means are set for oscillation of said pad carrier.

8. A machine according to claim 7, wherein said manually operable control means also have a setting at which said pad carrier remains stationary in respect of rotation about its axis of rotation as the body reciprocates, so that the same pad is operative each time said pad carrier is moved to the printing position.

9. A machine according to claim 8, wherein said actuating member is positioned to engage both said pawls so that the same are held out of engagement with said ratchet wheel when said manually operable control means are set for said pad carrier to remain stationary.

10. A machine according to claim 9, wherein means are provided to prevent changing said manually operable control means from one setting to another except when said body is at its position remote from the printing position.

11. A machine according to claim 10, wherein said manually operable control means comprise a control lever having different positions for the different settings.

12. A machine according to claim 11, wherein said control lever is coupled both to said actuating member and to said cam element for positioning them according to the positioning of said control lever.

13. An addressing or like printing machine, comprising a rotatable pad carrier, at least three printing pads supported on said carrier and disposed at intervals around the axis of rotation of the carrier, a body rotatably supporting said pad carrier, reciprocating drive means coacting with said body and reciprocating the same for moving said pad carrier to and from a printing position, manually operable control means, and means controlled by the setting of said control means and imparting to said pad carrier either an oscillation to and fro about its axis of rotation as said body reciprocates, so that two of the printing pads are alternately operative when said pad carrier is moved successively to the printing position, or a unidirectional step-by-step rotation as said body reciprocates, so that all of said printing pads are successively operative in cyclic order when said pad carrier is moved successively to the printing position.

14. A machine according to claim 13, wherein the means for either oscillating or unidirectionally rotating said pad carrier comprise an oscil-

12

lating element mounted on said body, and wherein means rotatably oscillate said oscillating element at half the frequency of reciprocation of said body, and wherein means rotatably oscillate said oscillating element at half the frequency of reciprocation of said body and couple the same to said pad carrier when said control means are set for oscillation of said pad carrier so that rotation of the oscillating element in both directions effects rotation of said pad carrier in both directions, and wherein said means rotatably oscillate said oscillating element at the frequency of reciprocation of said body and couple the same to said pad carrier when said control means are set for unidirectional step-by-step rotation of said pad carrier so that rotation of the oscillating element in one direction effects rotation of said pad carrier in one direction and its rotation in the other direction does not effect rotation of said pad carrier.

15. A machine according to claim 14, wherein said oscillating element is coupled to said pad carrier through the medium of a pawl and ratchet wheel device comprising two pawls for engaging a ratchet wheel for transmission in opposite directions respectively, and means are provided rendering both of said pawls operative when said manually operable control means are set for oscillation of said pad carrier, and rendering one of said pawls inoperative when said control means are set for unidirectional step-by-step rotation of said pad carrier.

16. A machine according to claim 15, wherein said pawls rotate with said oscillating element and said ratchet wheel is fast with said pad carrier, and wherein a cam element cooperates with the pawl which is inoperative when said manually operable control means are set for unidirectional step-by-step rotation of said pad carrier, so that the said pawl is moved thereby out of engagement with the ratchet wheel, at the time when the said pawl would otherwise engage a tooth of said ratchet wheel.

17. A machine according to claim 13, wherein said pad carrier comprises a hub element, a rotatable shaft supporting said hub element for rotation, a plurality of pad holders mounted on said hub element for respectively holding the pads, a plurality of radial rods one for each pad holder and each slidably in a respective radial hole in said hub element, each rod having an extension passing through a respective hole in said shaft and each pad holder being mounted on the outer end of the respective rod, spring means biasing said pad holders inwardly toward said shaft, and a plurality of screw adjusting elements each being screwed into said hub element diametrically opposite to the respective radial rod, each of said adjusting elements abutting against the extremity of the respective rod extension for adjusting the latter together with the respective radial rod and the respective pad holder and in opposition to the bias of the spring means.

18. A machine according to claim 17, wherein the rods and their extensions for the several pad holders are at different positions longitudinally of said shaft, the pad holders themselves being mounted so as to be all at the same position longitudinally of said shaft.

19. A machine according to claim 13, wherein the rotary movements of the pad carrier, whether during oscillation or unidirectional step-by-step rotation, take place during the movement of the body away from the printing position, and said

pad carrier is stationary in respect of rotation during the movement of said body to the printing position.

20. A machine according to claim 19, wherein locking means are provided for locking said pad carrier against rotary movement when said body is moved to the printing position.

21. A machine according to claim 20, wherein said locking means comprise a cam which rotates fast with said pad carrier and is formed with notches which correspond to the angular positions of said pad carrier at which the several pads are operative, a locking pawl biased to engagement with said cam so as to enter said notches and lock said pad carrier against rotation at the said angular positions, and means moving, at the commencement of each movement of said body away from the printing position, said locking pawl holding the said pawl away from said cam sufficiently long to enable said pad carrier to com- 10 15 20

mence rotating, the said locking pawl thereafter engaging said cam and entering the next notch to lock said pad carrier at the next position.

22. A machine according to claim 13, wherein the said pads are displaceably mounted on the pad carrier for adjusting the radial distance of said pads from the axis of rotation of said pad carrier.

ROBERT LEONARD KERR.
